ALBERT NELL, OF ST. LOUIS, MISSOURI

ELEVATOR-GATE-CONTROL MEANS

Application filed August 3, 1929. Serial No. 383,311.

My invention relates to improvements in elevator mechanisms, particularly to means for controlling the movement of the gate or door that is placed at each of the landing stages of the elevator.

My invention relates especially to such gates that are commonly used for freight elevator installations, and has among its objects the production of a safety mechanism 10 therefor, which shall be simple in operation and construction, convenient, economical, reliable, and efficient and satisfactory for use wherever found applicable.

The invention has for other objects, the 15 production of a device of the character described, in which the gate will be maintained in a locked position when the elevator is not adjacent the landing floor, but when the elevator reaches said floor, its movement or 20 travel will actuate control means to release the gate to permit the latter to be lifted so as to allow ingress to and egress from the elevator car, and at the same time will "set" a second locking element to hold the gate at its 25 raised position, permitting the lowering thereof only as the elevator car passes said floor.

Another object of my invention is to provide a mechanism for positively actuating the 30 gate toward its lowered position as the elevator leaves the particular floor at which the gate was left open or raised.

Many other objects and advantages of the 35 construction herein shown and described, and uses mentioned, will be obvious to those skilled in the art to which this invention pertains, from the disclosures herein given.

In the drawings, wherein like reference 40 characters indicate like or corresponding parts throughout the views,

Fig. 1 is an elevational view of my improved mechanism, as seen from inside the elevator car;

Fig. 2 is a side elevation of the same, with 45 a part of the counterweight pocket in cross-section;

Fig. 3 is a similar view to that shown in 50 Fig. 2, but with the latches held in position by the elevator car;

Fig. 4 is a view of the mechanism shown in Fig. 2, but at right angles thereto; and

Fig. 5 is a cross-sectional view, showing the gate and the spring-controlled means for actuating the same downwardly after the elevator car has passed the floor.

Referring more particularly to the drawings, wherein I have illustrated the preferred embodiment of my invention, 1 indicates the floor at one of the landing stages of the 60 elevator shaft, the side walls of the shaft being indicated at 2. At each of the floor landings there is a gate 3, of any suitable size and shape, preferably vertically slidable in a pair of opposed guideways 4 in the sides 65 2.

These gates are counterweights with one or more weights 5 and 6, arranged at the sides of the gate, each of the counterweights travelling vertically in a pocket or opening 7 in the side walls of the shaft, these counterweights being secured to the gate by the ropes or cables 8, passing over the pulleys 9. One of these counterweights, as the weight 5, may be provided with a series of ratchet teeth 10 along one face thereof, as shown and for a 75 purpose to be hereinafter described.

It is highly desirable, and in fact some municipalities specifically provide for the same by statute, that the gate at each floor be locked against opening unless the elevator 80 car be at that particular floor, and therefore to attain this end, and to prevent the accidental closing of the gate until the car passes the floor, I have invented the mechanism about to be described.

At each of the floors, I secure a base member 11, upon which is pivotally mounted a latch element 12, preferably having a bevelled end 13, with a downwardly extending prong 14, defining a slot 15 adapted to receive a suitable projection 16 provided on the gate 3. A slot 17 may be formed in the wall of the well to receive and conceal the prong 14, as shown. Obviously, when the latch 12 is in the position shown in Fig. 2, 85 the gate can not be raised.

A spring 18 normally urges the latch toward its locking position. A lever (as the bell-crank lever 19, is pivotally mounted at 20 on the base 11, the same engaging the lower 160

portion of the latch, through a pin 21 on the latter, said pin extending through an arcuate slot 22 in the member 11. As the lever 19 is rocked inwardly from its position 5 shown in Fig. 2, to the position shown in Fig. 3, such movement will move the latch to release it from engagement with the gate, against the pressure of the spring 18, so that the gate may be raised.

10 Pivoted intermediate its ends, at 23, is a second latch element 24, carried by the bell-crank 19 the rearmost end of the same moving in a slot 25 provided for the purpose in the bell crank 19, said latch element lying flat against the bottom of said slot as a limit 15 stop of pivotal movement. This latch element may be termed a "pawl", and has its forward end extended through an opening 26 of the wall structure of the elevator shaft, 20 and into the path of travel of the ratcheted counterweight 5. As the weight moves downwardly in its pocket, the pawl 24 will freely ratchet over the teeth, when the pawl is in its operative position shown in Fig. 3, but 25 any upward movement of said weight will be prevented, as the pawl will interlock with the teeth, the weight of the gate (in addition to the pressure of the positive gate-return mechanism not yet described) forcing the pawl against its seat at the bottom of the slot 25 in the base member 11.

The bell-crank lever 19 may be provided with an anti-friction roller 27, engageable with a projection 28 carried by the elevator 30 car 29. The length of the cam or projection 35 28 may be as desired, depending upon just how much difference between elevator car floor and landing floor is to be permitted. The longer the cam surface 28, the greater 40 will be the permissible distance between the landing floor and elevator car floor.

The operation of the mechanism is very simple, and is briefly, as follows:

When the car is distant from the floor, the 45 latch 12 will hold the gate against being raised. As the car moves toward the floor, the cam 28 will engage the roller 27 extending in its path, to thereby actuate the bell-crank lever to release the latch 12 and move the latch 24 into the path of the counterweight 5. Lifting the gate permits the teeth of the weight to ratchet over the pawl 24, but prevents upward movement of the weight by interlocking with the pawl, to thereby maintain 55 the gate in its raised position while the car is at the floor level. As soon as the car leaves the floor, the cam will move away from the roller, the spring 18 forcing the parts to their original position, and permitting the 60 gate to drop into its normal position latched against upward movement.

In order to cause a more positive action in lowering the gates to normal position, I have provided a projection 30 positioned 65 above the gate, in the path of travel thereof,

so as to be engageable therewith, the upward movement of the part 30 being against the pressure of a spring 31, connected thereto. The member 30 may comprise the rod having the elongated portion 32 about which the spring 31 is wound, the latter being secured at its lower end, said rod being bent forwardly at its upper end to form the projection to be engaged by the gate. A slot 33 is provided to form a guideway for the projection 30, this slot being provided in a casting 34 for the spring and rod, and the action of the return device is as follows:

The gate must be lifted to uppermost position against the tension of the spring 31, and is held in that position by the latch 24. As soon as the car moves past the floor, the latch 24 is thrown out of engagement with the counterweight by the action of the spring 18, and the spring tension acting on the projection 30 forces the gate downwardly to snap it past the latch 12. The tension of the spring 31 and the size of the counterweights may be adjusted as desired and found most suitable.

From the foregoing description it will be seen that I have invented a safety device for controlling the movement of elevator gates, in which the gates will be doubly locked against movement in both directions, and in which the gate will be positively returned to normal position after the elevator moves away from the floor.

It is obvious that various immaterial changes and modifications may be made in the construction just described; hence I wish it to be understood that such changes may be made without departing from the spirit of my invention and that I am not limited to the exact construction, arrangement and combination of parts herein shown and described, except as limited by the claims.

What I claim as new and desire to secure by Letters Patent is:

1. In a device of the kind described and in combination with an elevator gate, means to lock said gate against movement in one direction of its travel, means to lock said gate in the opposite direction of its travel, and a single means controlled by the movement of the elevator to release one of said locking means from its locking position and set the other of said means into locking position.

2. A control mechanism for the vertically movable gates for elevators, comprising means normally locking the gate against upward movement while the elevator is at a point distant therefrom, separate means to lock said gate against lowering movement, and a single means actuated by the elevator to release said first-mentioned locking means and set the other locking means in unison therewith into operatively locking position.

3. A safety device for elevator gates, comprising a pair of locking means alternately

engageable to lock said gate against movement in mutually opposite directions, and a single control means for said pair of locking means and adapted to be controlled by engagement with the elevator.

4. A mechanism of the kind described and in combination, comprising a vertically movable elevator gate having a weight thereon, a latch normally engageable with said gate to lock it against upward movement, a second latch normally out of engagement with said weight but movable into engagement therewith to lock the gate against lowering movement after having been raised, and a lever controlled by the movement of the elevator for actuating both of said latches.

5. A safety device of the kind described, comprising a slideable elevator gate carrying a ratchet weight, a latch normally engageable with said gate to lock it against movement in one direction, a second latch engageable with said weight to lock the gate against lowering movement but permit lifting thereof, and a lever controlled by the movement of the elevator for actuating both of said latching means in unison.

6. A mechanism of the kind described and in combination with an elevator gate, comprising a latch element movable into and out of locking engagement with said gate, a weight connected to said gate, a pawl element movable into and out of locking engagement with said weight to permit movement of the gate in one direction, and a bell-crank lever engageable with the elevator for actuating both of said locking means.

7. A safety device for elevator gates having a counterweight thereon, comprising a latch element movable into locking engagement with the gate, a bell-crank lever engageable by the elevator for actuating said latch element, and a pawl on said lever and movable therewith into locking engagement with said counterweight.

45 8. A safety mechanism for elevator gates, comprising a spring-pressed latch normally in engagement with said gate to prevent movement in one direction, a lever operable by said elevator for controlling said latch, and a second latch element on said lever and operable to prevent movement of the gate in the opposite direction after permitting its movement in the first-mentioned direction.

9. In combination with a vertically movable elevator gate having a ratcheted counterweight thereon, a lever mounted adjacent said gate in the path of travel of the elevator to be actuated thereby, a latch element normally in locking engagement with said gate to prevent lifting thereof and actuated by said lever to release said locking engagement, and a pawl pivoted intermediate its ends on said lever and movable into engagement with said ratchet teeth of the counterweight upon actuation of the lever to lock said counter-

weight against upward movement while permitting downward movement of the same.

10. In combination with an elevator gate, means for locking the same against downward movement, means for locking the gate against upward movement, a single means controlled by the movement of the elevator for operating both of said means in unison, and a spring-pressed means engageable with said gate while the latter is in raised position, for positively actuating said gate to lowermost position as the elevator moves away from said lock-controlling means.
